SELF-ALIGNING LOADING RAIL

Arthur J. Gaborc, Baldwin, and Mota Teumim, Middle-
town, N.Y., assignors, by mesne assignments, to the
United States of America as represented by the Secre-
tary of the Navy

Filed Feb. 27, 1961, Ser. No. 92,109

7 Claims. (Cl. 89—1.7)

The present invention relates generally to missile launchers and more particularly to an improved self-aligning loading-rail for a missile launcher.

With the advent of high performance turbo-jet, ram-jet and rocket propelled aircraft came the obsolescence of conventional anti-aircraft guns. Guided missiles traveling at speeds above Mach 1 and 2 with infra-red and radar homing systems have proved to be the only anti-aircraft weapons effective against these high performance aircraft.

In order to protect ground troops from bombing and strafing by these high performance aircraft these missile launching systems must have a high degree of mobility. Accordingly, missile launchers have been mounted on truck or trailer beds and kept at all times in the vicinity of the ground troops which they are supporting.

The missiles launched by many of these launchers are of considerable weight and must be transferred automatically from the missile transporting means to the launcher. Such a transfer system has been developed and is the subject matter of patent application, Serial No. 357,937, filed May 27, 1953, now U.S. Patent 2,978,959, by Robert E. Carlberg. Both this application and the present application have a common assignee.

In that device the missile launching system is mounted directly on the ground or on a mobile carriage which is capable of being moved from position to position within a battle area. Problems have been encountered in loading the missiles onto the launcher arm rail because, in many instances, the surface of the ground below this rail is often irregular. More specifically, when the truck or trailer is moving to a position beneath the rail during the transfer operation the truck carriage is caused to pitch and roll with the surface of the ground thereby making it difficult to load the missile onto the rail. In many instances, one of the two lugs on the missile will become properly positioned on the rail while the other will not. Further, when both lugs do properly engage the rail it is often difficult to precisely stop the loading truck at the exact position when proper engagement of the missile with the rail is attained. Thus, "over-running" occurs thereby causing one or more of the lugs to be severed from the missile or damage to the loading carriage and the missile launching arm.

Accordingly, it is an object of the present invention to provide an improved self-aligning loading rail.

A further object of the present invention resides in the improved means for aligning a missile launcher rail with a missile.

A still further object of the present invention provides a means to obviate launcher rail or missile damage due to over-run of the loading vehicle.

Another object of the present invention provides a means whereby a missile is securely stored on a missile launcher.

A still further object of the present invention is to provide a self-alignable guide means for a missile launcher which is simple in construction, reliable in operation, and relatively inexpensive in cost.

Other objects and many of the attendant advantages of this invention will be readily appreciated as the same becomes better understood by reference to the following

2

detailed description when considered in connection with the accompanying drawings wherein:

FIG. 1 is a side view of a missile launcher having a missile positioned thereon;

FIG. 2 is a side view partially in section showing a missile about to be transferred from the loading carriage to the launcher arm;

FIG. 3 is a side view partially in section of the U-lug way assembly;

FIG. 4 is a fragmentary perspective view of the front end of the U-lug way assembly;

FIG. 5 is a sectional view along a line substantially corresponding to line 5—5 of FIG. 3;

FIG. 6 is a side view, partially in section, of the T-lug way assembly;

FIG. 7 is a sectional view along a line substantially corresponding to line 7—7 of FIG. 6; and

FIG. 8 is a fragmentary perspective view of the rail alignment blocks.

In the embodiment of the present invention, as illustrated in FIG. 1, a mobile missile launcher 11 has had its front and rear carriages or bogie assemblies, not shown, removed. The base or stand 12 of the missile launcher 11 has bogie dudgeons 13 to which the bogie assemblies may be attached. The stand is provided with a pedestal 14 rigidly secured thereto and a trunnion support 15 rotatably mounted thereon. A trunnion tube 16 is supported by the trunnion support 15 and is operable to vertically rotate or elevate the arm 17. While only one arm 17 is shown mounted on the trunnion tube 16, the normal arrangement provides an arm on each side of the trunnion support 15. A guided missile 18 with its associated booster 18a and having a forward U-lug 19 and an aft T-lug 20 is received, stored, and launched by the rail which is suitably mounted on the arm 17. The term missile as used hereinafter is defined as including a missile with or without an associated booster. During operation of the system, signals received from the fire control system, not shown, are amplified and used to train or horizontally rotate the trunnion support 15 about pedestal 14 and to elevate the arm 17 thereby aiming the missile in the desired launch direction.

It is emphasized that the instant invention is applicable to any missile launcher which is to be loaded from a carriage which must move over an irregular surface during the transfer of the missile to the launcher and, consequently, is not limited to the herein described launching system.

The launcher rail is operable to receive a missile from a supply vehicle 23 having wheels 24, a forward U-lug mounting 25, and an aft T-lug mounting 26. The rail 22 is secured to the arm 17 by substantially identical linkage systems wherein sway links 31a and 31b having sway connections 32 therein are connected to the lift rod 33.

55 The sway links 31a and 31b have sway connections 32 positioned therein in a manner to permit rotary and lateral movements while prohibiting longitudinal movement of the rail. Lift rod 33 has a collar 34 rigidly secured thereto. Guide means 35 restricts lateral movement of the lift rod 33 while stop means 36 prevents downward movement of the lift rod 33 below the position shown in FIG. 2. The collar 34 has one end of thrust absorbing link 37 pivotally connected thereto while the other end of link 37 is pivotally connected to the stationary pivot 38. Link 37 opposes the bending forces applied to the lift rod 33 by link 44 and motor 47. The connection between collar 34 and link 37 is such as to compensate for the rotation of link 37. Bell crank link 41 has its ends pivotally connected to the stationary pivot 42 and the link 43 at pivot 41a. The link 41 is pivotally connected at 60 41b, through link 44, to the missile height compensator

65 38. Link 37 is pivotally connected to the stationary pivot 42 and the link 43 at pivot 41a. The link 41 is pivotally connected at 70 41b, through link 44, to the missile height compensator

45 which normally acts as a rigid connection between the link 43 and the output shaft 46 of the fluid motor 47. The piston 48 of the fluid motor 47 is reciprocated in response to fluid pressure flowing to and from the motor 47 via conduits 49 and 50. Guides 51 restrain the movement of the missile height compensators 45 and the fluid motor output shafts 46 to a linear direction.

Each height compensator 45 has a shaft 52 which is rigidly secured to the compensator housing. A piston or slide 53 is connected to the shaft 46 and has a spring 54 connected thereto. The spring 54 is also rigidly secured to the end of the compensator housing and under normal loading, as mentioned hereinbefore, the height compensator acts as a rigid connection. However, when the linkage is subjected to the unusually high forces the piston will stress the spring 54 and the height compensation 45 will absorb the movement generated by this force. Only the linkage system at the left hand of arm 17, as shown in FIG. 2, has been completely described as the linkage at the opposite end of the arm 17 is substantially identical.

Rail 22 has a forwardly positioned U-lug way assembly 60, FIGS. 3-5, and an aft positioned T-lug way assembly 70, FIGS. 6-7, which are operable to receive the correspondingly mounted missile lugs. For reasons of clarity, the U-lug way and T-lug assemblies 60 and 70 are not shown in FIGS. 1 and 2. The U-lug way assembly 60 has an entrance cam 61 which guides the U-lug 19 into the ways or grooves 62 which vertically support the U-lug 19 and, therefore, the missile. A U-lug feeler bar 63 is positioned on one side of the assembly 60 and is supported by parallel links 64. The feeler bar 63 is biased by spring 64 and link 65 in a downward direction in a manner whereby insertion of the U-lug 19 into the grooves or ways 62 effects upward movement of the feeler bar and actuation of switch 66. The ways or grooves 62 are continuous along each side of the assembly 60 thereby permitting the U-lug to pass from one end of the assembly to the other without restriction.

A firing contact 67 in the form of a laminated leaf spring is mounted on one side of the U-lug way assembly 60 and contacts the U-lug 19 of the missile when the lug is in the ram position, as shown by the dotted lines in FIG. 3. Guards 68 and 69 are provided on either side of the contact in order to protect this contact during loading from damage which might result from a lug which does not engage the grooves or ways.

The T-lug way assembly 70 has an entrance cam 71 which guides the missile T-lug 20 into the T-shaped groove or way 72, which vertically supports the T-lug and therefore the missile. The T-lug way assembly 70 includes a ram link 73 which pivots about connection 74, as shown in FIG. 6. A roller 75 is suitably mounted on the lower end of the ram link 73 and is effective to reduce friction and possible damage when the ram link 73 contacts the T-lug 20 during the ramming operation. The ram link 73 is positioned by the fluid motor 76 which acts through a ram piston shaft 77. A latch 78 is biased downwardly by spring 79 and automatically locks the shaft 77 in its retracted position as shown in FIG. 6. Means, not shown, are provided to retract the latch from its shaft locking position.

FIGS. 6 and 7 illustrate the firing latch mechanism 81 which includes a shear tip 82 which is cammed upwardly by movement of the T-lug in the loading direction, e.g. to the right in FIG. 6. The shear tip 82 is mounted on the member 83 which is pivotally connected to the rail by pin 84. Spring means 85 biases the member in the clockwise direction, as viewed in FIG. 7, while permitting the shear tip 82 and the member 83 to be cammed in a counter-clockwise direction by the movement thereunder of the T-lug in the loading direction. An output shaft 87 having a lost motion connection 88 therein connects the motor 89 with the link 90. Link 90 is in turn connected to the member 83. When the shaft 87 is in its upper-most position as shown in FIG. 7, the lost motion connection 88

permits limited counter-clockwise rotation of member 83 and the shear tip 82 thereby permitting the T-lug 20 to cam the shear tip upwardly out of its path. However, when the motor 89 positions shaft 87 in its lower-most position the lost motion connection 88 is taken-up and the member 83 and shear tip 82 are locked against counter-clockwise movement. Lever 91 is associated with the shaft 87 while lever 92 is associated with link 90. The levers 91 and 92 operate switches 93 and 94 respectively thereby indicating the position of the shaft 87 and member 83 on the launcher control panel, not shown.

The rear release latch 101 as shown in FIG. 6, is pivotally connected to the rail 22 by pin 102 and to the rear release link 103 by pin 104. Pivotally connected to the rear release link 103 by pin 105 is the rear release switch cam 106. As the missile T-lug 20 bears against the rear release latch 101, the resulting motion of the latch 101 moves the rear release link 103 upward causing the rear release switch cam 106 to actuate the release switch 107. Rear release spring 108 is interposed between the rail 22 and the rear release link 103 in the manner shown in FIG. 6. The roller 108 is positioned at the upper end of the rear release link 103 and contacts the portion 109 of the arm 17 when the rail 22 is raised to the firing position as will be explained in more detail hereinafter. When the loading truck 23 has overrun the rail 22 the lug 20 forces the rear release latch 101 in a counter-clockwise direction, as viewed in FIG. 6, thereby camming the latch out of its path. Thereafter, the lug 20 is free and continues through the T-lug way 72 thereby obviating any damage to the missile lugs 19 or 20 or to the way assembly 70. In other words, the rear release mechanism permits removing of the missile from the rail by allowing the truck to drive the missile lugs through the ways 62 and 72. However, when the rail assembly is raised to the firing position the rear release link 103 is locked against movement by contact of the roller 108 with the portion 109 of arm 17. Consequently the rear release latch 101 is positively locked against motion.

FIG. 8 illustrates one embodiment of alignment blocks 111 and 112 which may be used to properly position the rail 22 with respect to the arm 17 when the system is in the raised or firing position. The alignment blocks consist of a set of mating V-blocks 113 and 114 at each end of the sway link 31. These blocks insure accurate location of the rail 22 when in the raised position. The female block 113 is securely fastened by conventional fastening means 115 to the arm. This female block 113 has inwardly sloping surfaces 116 which will engage the complementary cam surface 117 of the male V-blocks 114. The male V-blocks are adjusted in a direction toward and away from the sway length 31 by turning of the bolts 118 thereby moving the V-blocks with respect to the base plate 119. Shims 121 interposed between the base plate 119 and the rail 22 adjust the height of the rail with respect to the arm when the rail is in the raised position.

In operation, when it is desired to load a missile onto the rail 22 the fluid motor 47 is actuated thereby moving its associated linkage to the position shown in FIG. 2, that is, moving the rail to a lowered position. In this position due to the sway links 31a and 31b the rail may be moved with respect to its axis angularly, radially, or any combination of these directions. When the rail 22 in the lowered position the loading carriage or truck 23 is driven thereunder. Because surface of the ground G is often irregular, the carriage 23 and the missile loaded thereon will have roll, pitch, and yaw movements as the T-lug and U-lug contact their respective entrance cams. The sway connection 32 permit rotary and lateral movements of the rail 22 but prohibit longitudinal movement thereof.

More specifically, contact of lugs 19 and 20 with the entrance cams 61 and 71, respectively, cause the rail to rotate and move laterally thereby effecting alignment of

the way assembly grooves with the appropriate lugs. In order to permit the height compensators 45 to perform properly, the rail is prohibited from moving in an axial or longitudinal direction, as explained hereinbefore. Restraining the rail from moving in a longitudinal direction prevents the rail from backing away from an oncoming lug, thereby permitting lug entry into ways 62 and 72.

Should the lugs 19 and 20 be too high with respect to ways 62 and 72 the rail will be cammed upwardly. This upward movement is absorbed by the one or both of the height compensators 45. For example, should the forward U-lug be higher than its way 62 it will first contact the entrance cam thereby forcing upwardly the sway link 31a, the link 33, collar 34 thereby moving linkage 44 to the right as viewed in FIG. 2. This rightward movement will be absorbed by the height compensating device as explained hereinbefore. The aft end of the rail assembly can be moved upwardly in a similar manner.

Once the lugs properly engage their ways the U-lug feeler bar 63 and a similar feeler bar, not shown, in the T-lug way assembly 70 actuate switches indicating that the lugs are properly positioned in the ways. Then the ram latch 78 is retracted and the ram fluid motor 76 actuated thereby moving output shaft 77 outwardly causing rotation of the ram link 73 about the pin 74 which, when the roller 75 contacts the T-lug, forces it in a rearward direction to the rammed or ready-to-fire position, as shown by the broken lines of FIG. 6. During movement to the ram position the T-lug 20 contacts the shear tip 82 causing it to be cammed upwardly. This upward movement causes the member 83 to be rotated about pin 84 and against the bias of spring 85. The lost motion connection 88 permits the member 83 to rotate in the counter-clockwise direction. When the T-lug 20 is in the ram position its rearward movement is resisted by the rear release latch 101 which is sufficiently biased by spring 108 to permit only extremely high forces on the T-lug to rotate it out of the way, e.g. movement of the truck. When in the ready-to-fire position forward movement of lug 20 is resisted by the shear tip 82. Once the T-lug is in the ready-to-fire position the ram link 73 is retracted and locked into the retracted position. It is to be noted that the U-lug way assembly 60 supports the missile only in a direction normal to the longitudinal axis of the rail and does not prevent the parallel movement of the U-lug. Once the lugs are in the ready-to-fire position the rail is moved to the raised position. In the raised position the rear release link 103 contacts the arm 17 at 109 thereby positively locking the rear release latch and insuring that the T-lug, and consequently the missile, will not move in the rearward direction. When the missile booster 19 is ignited without releasing the shear tip it builds up sufficient thrust to cause the T-lug to shear or break-off the shear tip 82 thereby releasing the T-lug and allowing the missile to move forwardly from the rail 22. The normal firing procedure is to actuate 89 to retract shear tip 82.

During the initial loading of the missile onto the rail should one or both of the lugs 19 or 20 fail to engage its ways 62 to 72 the appropriate feeler bar would not be actuated thereby indicating to the control panel operator that the loading must be attempted again. The operator effects the raising of the rail 22 and the loading carriage 23 is brought around for another pass.

Should the U-lug 19 engage its ways 62 and the T-lug 20 not so engage its ways 72 the U-lug 19 would merely pass through its ways and out the rearward end thereof. Should T-lug 20 engage its ways 72 but the U-lug 19 not engage its ways 62 the rear release latch 101 would be contacted by the T-lug 20 and rotated in the counter-clockwise direction thereby permitting the T-lug to move through its rail.

In summary, the above invention provides a completely universal loading rail which obviates difficulties encountered in loading a missile launcher from a carriage which

is being driven over an irregular surface. The present system provides means to insure a high probability of initial engagement of the missile lugs with the rail assembly together with means to obviate the possibility of damage to the missile or the launcher system in case the lugs do not initially become properly engaged.

Obviously many modifications and variations of the present invention are possible in the light of the above teachings. It is therefore to be understood that within the scope of the appended claims the invention may be practiced otherwise than as specifically described.

What is claimed is:

1. In a launcher for a missile having fore and aft positioned lugs carried thereby, said launcher comprising at least one arm member having movable rail means connected thereto, said rail means having fore and aft lugs thereon for receiving and supporting said lugs; a mechanism operable to move the rail means to a missile loading position and from a missile loading position to a missile launching position thereon, said mechanism including fore and aft lift means operatively connected to the arm member and the rail means and having means operable when the rail means is in said loading position to allow multi-angular and/or lateral movement of the rail means with respect to the longitudinal axis therefor; linkage means pivotally connected to said lift means and the arm member; a connecting link pivoted at one end to said linkage means; slidably mounted compensating means for facilitating disproportionate concurrent movement of both ends of said rail moving mechanism and having the other end of the connecting link pivotally connected thereto; fluid actuated means on the arm member movable in response to a predetermined change in fluid pressure and operably connected to said height compensating means for actuating said lift means through said compensating means, connecting link and the linkage means to move the rail to and from said loading and launching positions according to the movement of the fluid actuated means, said compensating means further including means carried by said fluid actuated means and cooperating with the compensating means for effecting independent movement of either of the lift means thereby to independently move either end of the rail means during missile loading movement; and spring means carried by the compensating means and cooperating with said means on the fluid actuated means for effecting proportionate movement of said lift means from missile loading to missile launching position as the fluid actuated means is operated by said predetermined change in fluid pressure; and means establishing an external pressure connection to the fluid actuated means.

2. A launcher for a missile as recited in claim 1 wherein said fluid actuated means includes a casing having a pressure chamber therein, a piston reciprocably slidably disposed therein, a shaft carrying said piston and slidably supporting the compensating means; and means on said shaft and slidably disposed within said compensating means in engagement with said spring means for actuating said compensating means, connecting link and the linkage means.

3. In a launcher for a guided missile-booster combination wherein the booster has an aft T-lug and a fore U-lug mounted thereon said launcher comprising a launcher arm, movable rail means connected to said launcher arm, said rail means having fore and aft lug ways carried thereby for receiving, supporting and releasing said lugs; fore and aft lift members slidably mounted on the launching arm and connected to the rail means;

a mechanism connected to said lift members for slidably moving the lift members to actuate the rail means from missile loading position to missile launching position and from missile launching position to missile loading position, said mechanism including linkage means; 5
means pivotally and drivingly connecting the linkage means to the lift members and to the launching arm; a fluid motor fixedly mounted on the launching arm; universal joint means in said lift members for allowing angular and lateral movement of the rail means when the rail means is in a loading position; 10
means on said launching arm and cooperating with complementary means on the rail means for preventing longitudinal movement of the rail means when the rail means is in a launching position; height compensating means interposed between said fluid motor and the linkage means; 15
means connecting said compensation means to said linkage means; 20
means including a piston carried by said fluid motor and slidably supporting the compensating means for effecting independent movement of the lift means and the corresponding ends of the rail means should the lug strike the rail means during movement thereof into the lug ways; and
spring means disposed within said compensating means in engagement with said piston for effecting proportionate concurrent movement of the lift members and the rail means to missile loading position. 25

4. A launcher for a guided missile-booster as recited in claim 3 wherein said linkage means includes first link member,
a second link member, and
a third link member,
said first link member being pivotally connected to the launcher arm and the second link member, said third link member being pivotally connected to the launcher arm and pivotally connected to said second link member;
collar means on said first lift members and cooperating with the pivoted connection between the second and third link member for providing a driving connection between the lift members and the linkages; and
an actuating rod pivotally connected to the compensating means and the second link and controlled by the fluid motor for actuating the linkage means thereby to effect concurrent proportionate movement of the lift members. 30

5. In a launcher for a guided missile-booster combination wherein the booster has an aft T-lug and a fore U-lug mounted thereon, said launcher comprising a launcher arm, movable rail means connected to said launcher arm, said rail means having fore and aft lug ways carried thereby for receiving, supporting and releasing said lugs; 35
fore and aft left members slidably mounted on the launching arm and connected to the rail means; a mechanism connected to said lift members for slidably moving the lift members to actuate the rail means from missile loading position to missile launching position and from missile launching position to missile loading position, said mechanism including linkage means; 40

means pivotally and drivingly connecting the linkage means to the lift members and to the launching arm; a fluid motor fixedly mounted on the launching arm; universal joint means in said lift members for allowing angular and lateral movement of the rail means when the rail means is in a loading position; means on said launching arm and cooperating with complementary means on the rail means for preventing longitudinal movement of the rail means when the rail means is in a launching position; height compensating means interposed between said fluid motor and the linkage means; means connecting said compensating means to said linkage means; means including a piston carried by said fluid motor and slidably supporting the compensating means for effecting independent movement of the lift means and the corresponding ends of the rail means should the lug strike the rail means during movement thereof into the lug ways; and spring means disposed within said compensating means in engagement with said piston for effecting proportionate concurrent movement of the lift members and the rail means to missile loading position; a shear tip mechanism having T-lug engaging means for restraining movement of said missile in a forward direction and a release mechanism having T-lug engaging means for restraining movement of the missile in a rearward direction when the rail means is in the launching position. 45

6. A launcher for a guided missile-booster combination as recited in claim 5 wherein said shear tip mechanism includes
a spring biased support pivotally mounted on the rail means;
a shear tip pivotally connected to said support;
a link pivotally connected to said support;
an output shaft connected to said link, and a fluid operated device connected to the output shaft for actuating the shaft to move the shear tip out of engagement with the T-lug. 50

7. A launcher for guided missile-booster combination as recited in claim 5 wherein said release mechanism includes
a latch member pivotally mounted on the rail means in engagement with the T-lug;
a spring biased actuating lever pivotally connected to said latch member and operated by the launcher arm to release the T-lug as the rail means reaches a missile launching position. 55
